UNITED STATES PATENT OFFICE.

WALLACE H. McCORMICK, OF STREATOR, ILLINOIS.

DUMPING MECHANISM FOR TRUCK BODIES.

Application filed May 5, 1923. Serial No. 636,891.

To all whom it may concern:

Be it known that I, WALLACE H. McCORMICK, a citizen of the United States, and resident of Streator, county of La Salle and 5 State of Illinois, have invented certain new and useful Improvements in Dumping Mechanism for Truck Bodies, of which the following is a specification, and which are illustrated in the accompanying drawings, 10 forming a part thereof.

This invention relates to trucks, and more particularly to dumping trucks or trucks in which the load is discharged by elevating one portion of the truck.

15 One of the objects of the invention is the provision of new and improved means whereby a body may be easily and readily tiltably mounted on chassis frames of different widths and types without in any way 20 injuring or weakening said frames.

Another object of the invention is the provision of new and improved body hoisting mechanism that is adapted to be mounted on chassis frames of various widths together with new and improved means for holding the body in normal position on the frame and for holding it in adjusted tilted 25 position during the dumping operation.

A still further object of the invention is 30 the provision of new and improved means for checking or controlling the descent of the hoisting body during its return to normal position on the chassis frame.

Other and further objects and advantages 35 of the invention will appear from the following description taken in connection with the accompanying drawings, in which:

Fig. 1 is side elevation of a portion of 40 dumping truck showing the body in elevated position, parts broken away;

Fig. 2 is rear elevation of one of the hoisting standards with a portion of the frame and the clamping plates in section;

Fig. 3 is vertical section of the same taken 45 on a plane extending longitudinally of the chassis frame;

Fig. 4 is detail view of a portion of the flexible hoisting members and the connecting member;

50 Fig. 5 is perspective view of a portion of the front end of the dumping body with the chassis frame in section and showing the application of the latching means;

Fig. 6 is a bottom plan of the latching 55 mechanism with parts of the vehicle in section and parts broken away;

Fig. 7 is a perspective view of a portion of the vehicle showing the hoisting mechanism attached thereto with parts broken away;

Fig. 8 is a perspective view of the rear portion of the chassis frame and body with the body in elevated position and showing the application of the hinge members thereto;

Fig. 9 is a section on line 9—9 of Fig. 8 with the body in lowered position, parts broken away;

Fig. 10 is detail view of a portion of the hoisting mechanism; and

Fig. 11 is a section on line 11—11 of Fig. 10.

On the drawing the reference numeral 10 designates a chassis frame comprising the longitudinal side members 11 and 12 and the rear cross member 13. The chassis frame is supported from the axle 14 by means of the springs 15 in the usual manner. A cab 16 is suitably mounted on the front of the chassis frame and is provided with the usual door opening 17.

A body 18 comprising the longitudinally extending side sills 19 and the transverse members 20 secured to the upper sides of the sills 19, is adapted to be mounted on the chassis frame. Suitable means are provided for pivotally or tiltably connecting the rear end of the dumping body to the chassis frame. The hinges or pivot connections are so arranged that they will accommodate bodies or chassis frames of various widths and the members of the hinges are so constructed that when the body is in lowered position on the chassis frame there will be no strain or weight on the pivot pins. As shown on the drawing, each hinge member

90 comprises an upper hinge fitting 21 and the lower hinge fitting 22. The lower hinge fitting 22 is preferably formed from angle plates 23 and 24 secured to the outer end of the rear cross member 13, by any suitable means such as the bolts 25 engaging in slotted openings in said plates. The slots permit lateral adjustment of the plates. In order to more firmly secure the lower hinge fitting 95 in position the rear portions thereof may be bent downwardly as shown at 26 and secured to the rear flange of the rear cross member by any suitable means.

100 The upper hinge fitting may comprise two angle plates 27 and 28 which are adapted to be secured to each side of the sills 19 with their lower flanges extending beneath the

110

same. The hinge pintle 29 is adapted to connect the hinge fittings together. The angle plates 23 and 24 are so arranged that the distance between their upstanding flanges is considerably greater than the thickness of the sills 19 whereby bodies of different widths may be pivoted thereto.

10 A collar 30 slidable on the pintle 29 having the setscrew 31 is adapted to properly position the body on the chassis frame. The hinge pintle 29 preferably extends immediately above the bottom flanges of the angle plates 27 and 28 and through the upstanding flanges of the plates 23 and 24 at such a 15 height that when the body is in lowered position on the chassis frame the plates 27 and 28 will rest on the fastening means 25 to thereby relieve the pintle 29 from supporting any of the weight of the body.

20 Suitable means are provided for maintaining the body in lowered position on the chassis frame. This means is preferably so arranged that it may be operated from the side of the body. As shown on the drawing, 25 this means comprises the two latch members 32 and 33 which are slidably mounted on the spacer member 34^a carried by the transverse member 34 which in turn is secured to the lower sides of the sills 19. These 30 latch members are maintained in proper position by suitable bolts 32^a and 33^a, carried by the transverse member 34 and engaging slots in said latch members.

35 The thickness of the spacer member 34^a is substantially that of the upper horizontal flange of the chassis frame members 11 and 12 whereby the latch members 32 and 33 will engage beneath the same to hold the body in lowered position on the chassis frame. A latch operating member 35 pivotally connected as at 36 to the transverse member 34 is adapted to be pivotally connected as at 37 and 38 to the inner ends of 40 the latch members 32 and 33 for operating the same.

45 A spring 39 connected to the bolt 33^a and to the latch or holding member 33 is adapted to maintain the latch members 32 and 33 in extended or latched position. A handle 40 connected to the free end of the latch operating member 35 and extending to the side of the body is adapted to retract the latch members 32 and 33. A keeper 41 is adapted to engage the inner side of stop 42 for holding the latch members 32 and 33 in retracted position.

50 Suitable hoisting mechanism for elevating the body is provided. This hoisting mechanism is so constructed and arranged that it may be detachably secured to chassis frames of various widths and designs. In the form of the device selected for illustrating one embodiment of the invention, journal or supporting plates 43 and 44 are adapted to be 55 adjustably clamped as by means of the bolts

45 to each of the longitudinally extending frame members 11 and 12 adjacent to the cab 16. By means of this arrangement the plates may be clamped at any suitable position along the frame members 11 and 12 to 60 accommodate frames or bodies of different lengths.

65 Suitable hoisting standards 46 are pivotally mounted between the plates 43 and 44. As shown on the drawing each standard 46 70 comprises a channel member, the web portion of which at its lower end is bent to form an eye 47 which is adapted to engage a spacing sleeve 48 mounted on one of the clamping bolts 45. The side flanges of the 75 member 46 are curved at their lower ends to correspond with the curve formed by the eye 47. The sleeve 48 extends through openings in the side flanges and engages the plates 43 and 44 to prevent the same from 80 being clamped against the standards 46. The upper ends of the standards are flattened out and may be provided with loop members 49 which are adapted to be secured to the web portion of said standards as by means 85 of the bolts 49^a and 50^b. Suitable guides or pulleys 50 are adapted to be mounted on journals or bolts 49^a in the loop members 49. The upper ends of the standards 46 are 90 connected together as by means of the cross member 50^a the ends of which are provided with slots 50^c through which the bolts 50^b extend. By this arrangement the lower ends 95 of the standards may be adjusted to chassis frames of different widths. 100

A hoisting shaft 51 is journaled in the plates 43 and 44. Flexible members or chains 52 having their lower ends connected to the shaft 51 are adapted to be trained over the pulleys or guides 50 and have their 105 free ends connected to the front end of the dumping body 18.

110 A connecting member 53 which is adapted to connect the flexible members or chains 52 at intermediate portions thereof and hold the same inwardly toward each other, may be employed to cause the chains or flexible members 52 to properly wind on the shaft 51 when the same is rotated.

115 Suitable means are provided for manually rotating the drum 51 for elevating the front end of the dumping body. As shown, the shaft 51 is extended outwardly beyond the chassis frame and is provided with ratchet wheel 54. A handle member 55 provided with a slot 56 in its inner end for engaging the shaft 51 is provided with a pawl 57 rigidly mounted thereon. The slot 56 in the handle member 55 permits the pawl 57 to engage or disengage the teeth of the ratchet 120 wheel. A spring 58 engaging a collar 59 is adapted to hold the handle member in frictional engagement with the inner face of the ratchet wheel 54. The handle member 55 is held in inoperative position by means of 125 130

the keeper 60 secured to the cab 16 which engages the handle 61 and prevents the rearward movement of the same. When the handle 55 is moved inwardly to engage the keeper 60 it compresses the spring 58 which in turn holds the handle member 55 in the said keeper. The shaft 51 is also provided with a ratchet 62 which is adapted to be engaged by the pivoted pawl 63 for preventing unwinding of the shaft 51. A stop element, such as the flexible member 63^a may be employed to limit the upward movement of the body.

The pawl 63 is held in engagement with the ratchet wheel by a spring 64. Suitable means are provided for releasing the pawl 63, from the side of the vehicle. As shown, a lever 65 is pivotally mounted on the cab 16 and its inner end is connected as by means of the flexible member 66 with the pawl 63 for releasing the same. A stop 67 is adapted to limit the movement of the lever 65 in one direction.

The standards 46 being pivoted as at 45 are free to turn about said pivots during the body raising and lowering operation, consequently there is not very much lateral thrust on these pivots. For the purpose of illustration these standards are shown in Fig. 1 as being out of contact with the body. In practice, however, the standards are in contact with the front end of the body during the raising and lowering thereof, as indicated in dotted lines in said figure. The friction of the chains 52 and standards 46 against the front end of the body tend to prevent a too precipitous descent of the body. In other words, by this arrangement the descent of the body is automatically controlled to a certain extent. It will be observed that the pivot bolts 45 for these standards are so located that little or none of the weight of the body is borne by them. The weight is supported by the lower ends of the standards resting on the upper flanges of the side bars 11 and 12 of the chassis frame.

If desired suitable braking means may be employed for controlling the descent of the body. For convenience of illustration this means is shown as comprising a band 68 having one end connected to the bolt 45, and its other end connected to the outer end of the pawl 63, and is adapted to be brought into engagement with the ratchet wheel 62 by the lever 65. The parts are so constructed and arranged that in moving the lever 65 downwardly the pawl 63 will first be disengaged and a further movement in the same direction will cause the brake band to engage a suitable brake drum as the ratchet wheel 62, as shown, to retard the unwinding movement of the shaft 51 and thereby control the descent of the body 18 from its elevated position.

The plate 69 on which the lever 65 is shown as being pivoted may be provided with a catch 70 for holding the lever 65 in lowered position. The catch 70 may be formed on the plate 69 by making an incision in the lower edge thereof and bending one of the corners outwardly.

When the body 18 is in the lowered position the forward end of the same is supported on the chassis frame by means of the cross member 34. The sill 19 may be notched as at 690 for providing a clearance for the outer end of the shaft 51. Likewise, the intermediate portion of the end of the floor which normally extends forwardly beyond the front cross member 71 may be cut away or removed to form a recess 72 in which the standards 46 are adapted to engage when the body is in lowered position. By this arrangement the body can be brought up against or substantially contiguous to the rear end of the cab 16.

It will be understood that various changes in the form, construction, composition and arrangement of the several parts may be resorted to without departing from the spirit and scope of my invention; hence I do not wish to limit myself strictly to the structure herein set forth, but

What I claim is:—

1. In combination, a chassis frame comprising longitudinal and transverse frame members, a body provided with side sills, a plurality of hinges for connecting said body to said chassis, each hinge comprising a hinge fitting secured to one of said sills, said fitting comprising oppositely arranged angle plates having bases and upstanding flanges engaging the sides and under surface of said sill and secured thereto, a corresponding hinge fitting comprising oppositely arranged angle plates having bases and upstanding flanges adjustably secured to said transverse frame member, and a rod for pivotally connecting said flanges together.

2. In combination, a chassis frame comprising longitudinal and transverse frame members, a body having side sills mounted thereon, a hinge fitting secured to one of said sills, a hinge fitting secured to said transverse member, said last-named fitting comprising angle plates engaging said transverse member, and having upstanding flanges thereon, the distance between said flanges being materially greater than the width of said sill, a hinge pintle extending through said flanges and said first-named fitting and means on said pintle for adjustably securing said first-named fitting along said pintle.

3. In combination, a chassis frame having channel side members, a body hinged to said frame, slidably mounted latch members for

engaging beneath the flanges of said channel side members securing said body to said frame, a toggle link pivotally connected to said members for operating the same, spring means for holding said members in latched position, a handle for operating said link, a keeper for said handle, and means on said handle for engaging said keeper for holding said members in unlatched position against the tension of said spring.

4. In a device of the class described, a chassis frame, a body pivoted thereon, mechanism for hoisting one end of said body, said mechanism including a rotatable hoisting shaft, a ratchet wheel thereon, a crank having a slot within which said shaft engages, a pawl carried by said crank for engaging said ratchet wheel, a spring engaging said crank, and a clip on said body for engaging said crank and holding the same against the tension of said spring.

5. An attachment for dumping trucks comprising journal plates, bolts for clamping said plates to a chassis frame, hoisting members comprising channel shaped standards, the side flanges at the lower end of said standards being curved, and the web portions thereof bent to form bearing members, spacing sleeves journaled in said bearings, certain of said bolts extending through said sleeves, pulley supporting members secured in said channels at the upper ends of said standards and pulleys journaled in said supporting members.

35. 6. In combination, a chassis frame, a body

pivoted thereon, hoisting mechanism for said body including hoisting standards, pulleys mounted on the upper ends thereof, a rotatable hoisting shaft, flexible members connected to said shaft and body and trained over said pulleys and a connecting member for the intermediate portions of said flexible members to guide the winding of the same on said shaft.

7. An attachment of the class described, comprising supporting plates, means for clamping a pair of said plates to each of the longitudinal members of the chassis frame of a motor vehicle, hoisting standards, each comprising a channel member having the lower end of its web portion bent to form an eye, a pin for pivotally connecting said eye to said plates, a rotatable hoisting shaft journaled in said plates, guides carried by the upper ends of said standards, flexible members secured to said shaft and trained over said guides, and a cross member adjustably connected to the upper portions of said standards.

8. In combination, a chassis frame, a cab on the front end thereof, a body pivotally mounted thereon, means for elevating said body, said means including standards mounted on said frame adjacent to the rear of said cab, the front end of said body having a recess for receiving said standards whereby when said body is in lowered position the front end thereof is contiguous to said cab.

WALLACE H. McCORMICK.
